UNITED STATES PATENT OFFICE.

LISA E. ERBEAU, OF CAMDEN, NEW JERSEY.

CONVERTIBLE CHAIR.

1,389,940.

Specification of Letters Patent.

Patented Sept. 6, 1921.

Application filed September 18, 1920. Serial No. 411,223.

To all whom it may concern:

Be it known that I, LISA E. ERBEAU, a citizen of the United States, residing in the city and county of Camden, State of New Jersey, have invented a new and useful Convertible Chair, of which the following is a specification.

My invention consists of a chair that is convertible to various uses, more particularly for children, such as a low or high chair or for toilet use, and may be folded in compact form for transportation, carried by hand, packed, stored, etc., the construction being hereinafter described and the novel features thereof pointed out in the claims.

The invention is satisfactorily illustrated in the accompanying drawing, but the important instrumentalities thereof may be varied, and so it is to be understood that the invention is not limited to the specific details shown and described, as long as they are within the spirit or scope of the claims.

Figure 1 represents a perspective view of a child's chair embodying my invention.

Figs. 2 and 3 represent perspective views in reduced scale of the chair in partly folded condition.

Fig. 4 represents a perspective view of the chair in completely folded condition.

Fig. 5 represents a perspective view of the chair in use with a water closet bowl.

Fig. 6 represents a side elevation of the chair on a reduced scale as converted into a high chair.

Fig. 7 represents a vertical section of portions of Fig. 6 on an enlarged scale.

Fig. 8 represents a transverse section on line 8—8 Fig. 7.

Fig. 9 represents a bottom plan view of the chair.

Fig. 10 represents a side elevation of the chair in folded condition.

Fig. 11 represents a transverse section on line 11—11 Fig. 9 on an enlarged scale.

Fig. 12 represents a front elevation of the seat portion of the chair on a reduced scale.

Fig. 13 represents a vertical section of the hinge portions of one of the arm rests on an enlarged scale.

Fig. 14 represents a vertical section thereof on line 14—14 Fig. 13.

Fig. 15 represents a vertical section of a portion on line 15—15 Fig. 1 on an enlarged scale.

Fig. 16 represents a top or plan view of

mechanism for locking the side arms preventing folding thereof.

Fig. 17 represents a side elevation thereof, and sections of an arm rest and back of the chair with which said catch mechanism are connected.

Similar numerals of reference indicate corresponding parts in the figures. Referring to the drawings,

1 designates the seat of the chair, the same having therein an opening which may be placed on a chamber pot or the bowl of a water closet when the chair is placed over the same, said opening having a cover 2 for closing purposes.

3 designates the back of the chair which is hinged at the bottom to the rear of the seat and 4 designates a supplemental back which is stationarily connected with said rear and adapted to support said hinged back, and when the latter is lowered or folded provides another back for the chair.

5 designates the arm rests of the chair, the same being hinged to the sides of the seat and are adapted when the back 4 is in folded condition to be folded upon the same.

6 designates the legs of the chair, the same being hinged to the underside of the seat as at 7, whereby they may be folded upwardly against the underside of the seat. In order to retain said legs in operative condition as shown in Figs. 1 and 6, I provide the brace or stretcher 8 composed of opposite bars or pieces which are hinged at their outer ends to said legs as at 9. The inner ends of said legs are adapted to be connected by the sliding sleeve 10 which embrace said ends and so retain the brace against separation, but when said sleeve is moved to the right or left, the ends of the members of the brace are uncovered and disconnected and so the bars or pieces may be folded on the legs and the latter folded with the same against the underside of the seat, it thus being seen that the chair as thus constituted may be compactly folded, convenient for purposes of carrying by hand, transportation, packing, storage etc.

When the legs 6 are in operative positions, the chair forms what I term a low chair, but in order to convert it into a high chair I provide the bottom of said legs with sockets 11 which are open below and closed at the top and into the same I fit the additional legs 12, see Figs. 6, 7 and 8, as extensions of the

legs 6, thus raising the seat 1 and rendering the chair serviceable as a high chair. These sockets are hollow members secured to the legs and have closing walls at top, see said Fig. 7, so as to limit the upward movement of the legs by the abutment of the top edges of said legs against said walls and so sustain said legs in a firm and steady manner. When the chair is at normal height as in Fig. 1, 10 the sockets 11 being on the sides of the lower ends of the legs 6, form feet on which said legs are supported in addition to the legs themselves on a floor, and provide broad bases as feet for steadyng said legs and consequently the chair and form reinforcements for the lower ends of said main legs 6 and avoid boring said ends to receive the extension legs.

The chair is provided with the tray 13 20 which is journaled by the dowels 18* with the arm rests 5, whereby it may be raised and lowered as usual in such cases and serve to prevent the arms from closing in front.

In order to lock said arm rests at their rear 25 portions and prevent inward motion thereat there are connected with the sides of the supplemental back 4, the chains or flexible members 14 with which are connected the balls or heads 15 the latter being adapted to 30 engage the bifurcated catches 16 on the arm rests 5 of the chair, it being noticed that the flexible members 14 enter said catches and the balls or heads 15 drop in front of the latter and so retain said members in position 35 and connect the arm rests with the back preventing the former from improper folding, this being particularly serviceable when the hinged back 3 is in folded position on the seat 1.

40 When the balls or heads and flexible members are raised from the catches 16 and so released from the same, the arm rests are unlocked from the back 3 and they may be folded as hereinbefore stated.

45 In order to connect the chair with a chamber pot or water closet bowl and prevent it from slipping therefrom there are connected with the underside of the seat the resilient jaws 17 of elbow form and adapted to be 50 spread apart so as to be fitted over the flange of the pot or bowl and then spring toward each other closed on the same, thus retaining the chair in position while it is in use.

In order to operate said jaws 17 so as to 55 separate or open them there are connected with the same the rods 18 forming handles

which are slidngly mounted in ears 19 on the underside of the seat and accessible at the sides of the latter, as most plainly shown in Figs. 9, 11 and 12.

The rear of the seat has connected with it the hook-like member 20 which may be engaged with the wall of the top of the chamber pot or bowl or seat portion of the latter as means for additionally connecting the 65 chair with said pot, or bowl or seat portion.

Having thus described my invention what I claim as new and desire to secure by Letters Patent, is:—

1. A chair of the character stated, comprising a seat, a back hinged thereto, a supplemental back fixed to the rear of said seat, side arms hinged to the sides of the seat, and means connecting the rear ends of said arms with the ends of the top member of the last- 75 named back.

2. In a convertible chair, a seat, main foldable legs proper hinged thereto, folding stretchers for said legs, tubular socket pieces on the lower ends of said legs, extension legs, 80 said socket pieces being adapted to receive the upper ends of said extension legs and limit the upward motions of the latter, said socket pieces primarily forming broad bases and reinforces for the lower ends of said main legs. 85

3. In a chair of the character stated, a seat, a back hinged thereto, a stationary back adapted to support the former in upright position, side arms hinged to the seat to fold inward toward each other and to lie against 90 said hinged back when the latter is in its vertical position, and means embodying bifurcated catches, heads adapted to engage said catches, and flexible members carrying said heads and connectible with said stationary back for preventing said arms from folding while permitting the hinged back to fold on the seat.

4. A chair of the character stated, comprising a seat, a back hinged thereto, a supplemental back fixed to the rear of said seat, side arms hinged to the sides of the seat, means connecting the rear ends of said arms with the ends of the top member of the last-named back, and means on the supplemental 100 back engageable with the arms of the chair to lock the rear ends of said arms and prevent inward motion of the latter.

LISA E. ERBEAU.
